UNITED STATES PATENT OFFICE.

JOHN JACHENS, OF SAN FRANCISCO, CALIFORNIA.

PRINTING DEVICE.

1,199,385.

Specification of Letters Patent. Patented Sept. 26, 1916.

Application filed March 16, 1914. Serial No. 825,167.

To all whom it may concern:

Be it known that I, JOHN JACHENS, a citizen of the United States, residing in the city and county of San Francisco, State of California, have invented a certain new and useful Improvement in Printing Devices; and I do hereby declare the following to be a full, clear, and exact description of the said invention, such as will enable others skilled in the art to which it most nearly appertains to make and use the same.

This invention relates to a new article of manufacture, and more particularly to printing type and the means for assembling and impressing the same.

Among the objects of this invention are: To provide means for quickly and easily setting up or assembling type in a line, and to impress the composition on yielding surfaces such as wood leather and the like; to provide a convenient holder for the type, so formed, that the whole pressure is exerted on each type *seriatim*; to combine with the holder a protective guard for the type faces when not in use, and a storage space for extra type; to provide a catch in said holder to receive the opposite ends of a chain.

Other objects and advantages will appear as the description progresses. Variations and modifications within the spirit of this invention as defined in the claims succeeding said description, may be made in the practice of this invention.

In the drawings forming part of this specification, to which like letters of reference have been applied; Figure 1— is a front elevation of an article of manufacture constructed in accordance with this invention, one of the type guards being shown partly opened. Fig. 2— is a vertical cross section on the line II—II, of the same. Fig. 3— is an edge view of a type member constructed in accordance with this invention. Fig. 4— is a plan view of a type blank from which the type is formed.

In detail the construction illustrated in the drawings includes the holder 1, preferably struck from sheet metal of the desired thickness, having the central opening 2 there through forming an annular ring. The back of the holder is covered by the plate 4 fixed thereto. The front of the holder is provided with the frame 5, following the contour of the holder and the opening 2. The backing plate 4, and the frame 5, are

rigidly fixed to the holder by the rivets 6—6 and 7 passing therethrough. The edges of the plate 4 and frame 5 are concentric with the edge of the holder and are of less diameter; the edges 8 and 9 of the plate and frame respectively, are elevated above the plane of the holder and have the concentric grooves 10 and 11 struck up from the body of the plate 4 and frame 5, these grooves extending around the lower half of the holder. 60 The back plate 4 and the frame 5 are both provided with a gap 12 in alinement on both sides of the holder, extending from the edge inward, beyond the grooves 10 and 11.

The type members are blanked as shown 70 in Fig. 4, the body portion 14, having the character 15 struck up or embossed thereon. The extensions 16—16 extending laterally from the body portion have the upturned edges 17—17 thereon. These extensions 75 16—16 taper from the width of the body 14, so that their edges lie together on radial lines, from the center of the holder, when assembled thereon as in Fig. 1; the blank is bent at substantially a right angle at 80 18—18, Fig. 3. The width of the body portion 14, between the upstanding extension 16—16 is just slightly greater than the cross section of the holder 1.

The type are preferably formed of hard 85 spring metal, as thin as practicable. The type are assembled on the holder by pinching the sides 16—16, inserting over the edge of the holder, with the bent ends extending into the gaps 12; the type is then slid around 90 into position, with the upturned edges 17—17 engaging the grooves 10 and 11, and are held in position by the expansion of the compressed sides 16—16.

To assist in setting up or assembling the type, to spell the desired word, the character 15, which for obvious reasons must be reversed, is duplicated with a like character 19, reading straight or not reversed on the front side extension 16, so that the legend set 95 up by the type reads straight from left to right; this has the additional advantage of serving as a name tag for identification.

It is preferable to form the characters 100 15 with a sharp face, to aid in forcing them into the surface to be marked. With the name set up on the holder, the name can be impressed on any yielding surface, such as the wood covering of lead pencils, the leather binding of books, hat bands, photo-

graphs and other suitable objects to be marked. The impression is accomplished by grasping the holder between the thumb and fingers and rolling the printing edge 5 along the surface to be marked. The advantage of the circular holder being that in its mode of operation, the whole pressure is exerted progressively upon each character or a part thereof, at a time. It is obvious that this operation permits the sinking of the type dies into the surface with greater facility, than if it were attempted to force the whole word or group of dies into the surface, at the same time.

15 The opening 2, covered at the back by the plate 4 is provided with the cover 21, hinged at 22'-22' in the holder, completely covering the opening 2, to convert the latter into a space for containing extra type, identification data etc.

When not in use, the faces of the type are covered by the inclosing guards 22 and 23, respectively pivoted on the rivets 6-6. These guards are preferably channel or U 25 shaped in cross section. The end of the guard 22 is provided with a notch to receive the pin 24, on the spring extension 25, on the guard 23, when the ends of the guard are brought together. The cover 21 is locked in a 30 closed position, by the overhanging flanges 26 on the heads of the guards 22 and 23 until the guards are swinging back as indicated in Fig. 1, in which position the flanges 26 no longer overlap the edges of the cover.

35 A further utility is added to the present implement, by the addition of the key chain 27, having the rings 28-28 engaging the hooks 29-29 formed on the holder 1, Fig. 1. The extension points 30-30 on the cover 40 21, overhanging the edges of the hooks 29, to prevent the disengagement of the rings 28 with the hooks, until the guards are opened and the cover 21 released as 45 previously described; by this combination the ends of the chain are double locked against disengagement.

Having thus described this invention, what is claimed and desired to secure by Letters Patent is:—

50 1. A printing device, including a flat holder; plates on the sides of said holder; grooves in said plates; a type member having spring sides with outstanding ends engaging said grooves.

55 2. A printing implement including a circular holder, U shaped type engaging said holder; guards pivoted in said holder encircling the circumference and covering said type; a chamber in said holder, a cover 60 hinged on said holder covering said cham-

ber, the edge of said cover lying under a flange on said guard, in the closed position.

3. A printing implement including a circular holder; plates on said holder, grooves in said plates; U shaped type having bent ends 65 engaging said grooves; a chamber in said holder; a cover hinged on said holder; guards pivoted on said holder encircling the circumference of the holder over said type; a flange on said guards overhanging 70 the edges of said cover in the closed position.

4. A printing device including a holder; plates on said holder having grooves therein; a type member having spring sides with 75 bent ends engaging said grooves; guards pivoted on said holder encircling the circumference of said holder and covering said type; and a reading character on said type exposed between said guards and the edge 80 of said grooved plates.

5. A printing device, including a curved holder, grooved plates on said holder; a gap in said plates at one end of the grooves therein; a type member having spring sides 85 with bent ends engaging said grooves; guards pivoted on said holder encircling the circumference of said holder and covering said type; and a reading character on said type exposed between said guards and the 90 edge of said grooved plates.

6. A printing implement including a circular holder; U shaped type engaging said holder; guards pivoted on said holder encircling the circumference of the holder 95 and covering the printing face of said type; a hook on said holder; a cover hinged on said holder engaging said hook, and a flange on said guard engaging said cover in the closed position.

7. A printing implement including a circular holder; grooved plates on said holder having gaps therein open to one end of said grooves; U shaped type having bent ends 105 engaging said grooves; guards pivoted on said holder encircling the circumference of the holder over the printing face of said type; reading characters on the sides of said type between the edges of said plates and said guards; a hook on said holder; a cover hinged on said holder and engaging said hook; and a flange on said guard overhanging the edge of said cover.

In testimony whereof, I have hereunto set my hand this 9th day of March 1914.

JOHN JACHENS.
